UNITED STATES PATENT OFFICE.

DAVID EWART, OF OTTAWA, CANADA.

CONSTRUCTION OF CONCRETE WALLS.

No. 829,829.

Specification of Letters Patent.

Patented Aug. 21, 1906.

Application filed August 1, 1905. Serial No. 272,255.

To all whom it may concern:

Be it known that I, DAVID EWART, a citizen of the Dominion of Canada, residing in the city of Ottawa, county of Carleton, and Province of Ontario, Canada, have invented a new and useful Improvement in the Construction of Walls of Buildings, of which the following is a specification.

My invention relates to improvements in the construction of concrete walls; and it consists in the herein-described placing and arrangement of the materials used. The object of my invention is to provide a wall that will possess the advantages of a fireproof solid concrete wall and that will at the same time include an air-space behind its inner or lath-and-plaster facing, that will be simple and inexpensive in construction, employing light and easily-handled material, and, further, that may be finished with the plainest or the most ornamental design.

The process of erecting a wall embodying my invention is fully hereinafter described, reference being had to the accompanying drawings, in which—

Figure 1 is a plan view, Fig. 2 an outside elevation, Fig. 3 an inside elevation, and Fig. 4 a cross-sectional elevation, of a portion of the wall as in process of construction. Fig. 5 is a part sectional plan view of the finished wall.

The same letter in the different figures indicates the same part of the structure.

Two rows of light studs A and A', that may be either of wood or metal, as preferred, are placed in pairs, as shown, and the two studs of each pair are held at such distance apart as will suit the desired thickness of wall by tie-pieces B, secured to the studs at convenient distances apart.

The outer edges of the outside studs A are set at a short distance back from the intended outer face of the wall, and gage-blocks C hold a facing-board D at that distance from the studs A. This allows the concrete to fill around in front of the outside studs and form against the facing-board the smooth-finished outer face of the wall. The facing-boards D are held in place while filling in the

concrete by screws d'. The penetration of 50 the wall by heat, cold, or moisture is provided against by an air-space between the concrete and the lath-and-plaster course forming the inner face of the wall. This space is formed by placing a curb-board E equal in 55 thickness to the size of space desired between each pair of studs. (See Figs. 1 and 3.) These curb-boards are removable and when in use are held in position flush with the face of the inside studs A' by cleats F, tacked to 60 the studding. When the facing-board D and curb-boards E have been set in place, the concrete G is filled in to any suitable depth and may be continued as a course around the building. When such a course of the concrete 65 has set sufficiently hard, the facing-board D and curb-boards E are raised and secured to the studding higher up, where they will be in position to receive a further course of concrete. The process of laying concrete courses 70 as above described is repeated until the desired height of wall is reached.

Where the floors occur, the inside studs A' are cut away to receive the joists H, which rest upon them, and as the joists and studding would be preferably of the same thickness there will be no impediment to the raising of the curb-boards E. I indicates the air-chamber between the concrete G and the lath d', secured to the inside studs A'. 75 80

In the above-described improvements in the construction of concrete walls I claim as my invention and desire to secure by Letters Patent—

A building-wall composed of two separated 85 rows of studs the studs of the opposite rows being tied together and spaced apart in pairs transversely of the wall; and a body of concrete by which the outer row of studs is surrounded, and from the inner face of which the 90 inner row of studs project for some distance to form an air-chamber between it and the lath and plaster secured to said inner row of studs.

DAVID EWART.
